[57] CLAIM

The ornamental design for an element of a shoe upper, as
shown and described.

DESCRIPTION

FIG. 1 is a side elevational view of a shoe upper having an
element showing my new design;

FIG. 2 is a top plan view thereof;

FIG. 3 is a front elevational view thereof; and,

FIG. 4 is a rear elevational view thereof.

The broken line showing of the remainder of the shoe,
including the lacing elements, is for illustrative purposes and
forms no part of the claimed design.
